UNITED STATES PATENT OFFICE.

SAMUEL BARUCH, OF NEW YORK, N. Y.

SPRING OILER.

Application filed April 12, 1923. Serial No. 631,512.

To all whom it may concern:

Be it known that I, SAMUEL BARUCH, a citizen of the United States, and resident of New York, in the county of New York and State of New York, have invented certain new and useful Improvements in Spring Oilers, of which the following is a specification.

This invention is an improved oiler for laminated springs of the character commonly employed on vehicles.

Among the objects of my invention are to provide a device which may be easily and quickly attached or removed without the aid of tools; which is securely held without liability of rattling, but without locking or binding the spring or interfering with the relative movement of the laminations; which will remain in place without working lengthwise along the spring; which will support the lubricant in direct contact with the edge of the spring, and which is neat and inconspicuous and inexpensive to manufacture.

I have illustrated one embodiment of my invention in the accompanying drawings, in which—

Fig. 1 is a side elevation showing the device applied to a spring.

Fig. 2 is a transverse section on the line 30 2—2 of Fig. 1.

Fig. 3 is a perspective view of the frame part of the device, and

Fig. 4 is a perspective view of the lubricant container.

In the device illustrated there is provided a substantially U-shaped frame member cut from a single piece of sheet metal bent to form a plate or end wall 10 constituting the web portion, and top and bottom walls 11 and 12. The top and bottom walls are preferably non-parallel and converge in the direction of the length of the spring so that when the frame is attached to the spring with the edges of the top and bottom walls which are nearest together toward the thinner end of the spring, the frame may move endwise along the spring toward the thicker portion of the spring to a predetermined point where it will remain in position. Springs as ordinarily mounted on automobiles have the thinner portion of the spring, that is the portion of fewest laminations, extending upwardly or at a higher elevation than the thicker portion having the maximum number of laminations. Therefore the converging walls will limit the movement in

one direction while gravity will prevent movement of the frame in the other direction.

The end wall 10 serves to hold in place a lubricant container. This is shown as a cup 13 extending through an aperture 14 in the end wall 10, and having its inner end open directly toward the edges of the leaves or laminations of the spring. To prevent leakage of the lubricant between the container and the spring the container is provided with a peripheral flange 15 lying in a plane substantially parallel to the end wall 10, and between this flange and the spring there is placed an annular washer or gasket having a central aperture permitting the direct contact of lubricant in the container with the edge of the spring. This washer may be comparatively narrow but is shown with a central opening of approximately the same size as the interior of the container. The flange 15 preferably has a marginal portion 17 encircling the gasket to hold the latter in position, and the gasket is of slightly greater thickness than the width of this marginal portion or edge, so that said edge cannot directly contact with the spring.

Resilient means is provided for pressing the container toward the edge of the vehicle spring. This resilient means is shown as a spring 18 disposed between the end wall 10 and the flange 15, and encircling the container 13. The spring is preferably of substantially conical type, so that it may be pressed into the minimum space. The frame is held in place on the vehicle spring by any suitable form of retainer, as for instance a cotter pin 19 extending through the apertures in the extremities of the top and bottom walls 11 and 12. These walls are spaced apart to a distance slightly greater than the thickness of the vehicle spring so that the laminations may separate slightly during the action of the spring.

It will be noted that the spring 18 holds all of the parts in position and against rattling, as well as pressing the gasket or washer to prevent escape of the lubricant except between the laminations. The lubricant being in direct contact with the edges of the laminations can work in between them, and will thoroughly lubricate the parts.

To remove the device it is merely necessary to press the end wall 10 toward the spring which will free the cotter pin from

the opposite edge of the spring and permit of its removal. With the parts removed from the vehicle spring the container may be easily refilled with oil, grease or other desired lubricant. The spring 18 is concealed from view and protected by the plate 10, and as the walls of the frame substantially follow the top, bottom and edge surfaces of the vehicle spring the device is inconspicuous.

Having thus described my invention, what I claim as new and desire to secure by Letters Patent is:

1. A lubricating device for laminated springs, including a lubricant container having an open end and a peripheral flange, an annular gasket engaging with the face of said flange, and a frame having an opening receiving said container but smaller than said flange.

2. A lubricating device for laminated springs including a frame encircling the spring, a lubricant container having guided movement in respect to said frame and toward and from the edge of the spring, and resilient means disposed between said frame and said container.

3. A lubricating device for laminated springs, including a frame adapted to encircle the spring and having a perforated plate portion, and a lubricant container having a portion guided therein and movable in respect thereto toward and from the edge of the spring.

35 4. A lubricating device for laminated springs, including a frame adapted to encircle the spring and having a perforated plate portion, a lubricant container having a portion guided therein and movable in respect thereto toward and from the edge of the spring, and resilient means tending to hold said frame and container against relative movement.

45 5. A lubricating device for laminated springs, including a U-shaped frame member having a web portion disposed opposite to but spaced from the edges of the laminations, and a lubricant container between said edges and said web, and having a portion projecting through said web portion.

50 6. A lubricating device for laminated springs, including a U-shaped frame member having a web portion disposed opposite to but spaced from the edges of the laminations, a lubricant container between said

edges and said web, and a spring disposed between said web portion and said container for holding said container against the edges of the laminations.

7. A lubricating device for laminated springs, including a U-shaped frame member having a web portion disposed opposite to but spaced from the edges of the laminations, a lubricant container between said edges and said web, and a spring for holding 65 said container against the edges of the laminations, said last mentioned spring encircling said container.

8. A lubricating device for laminated springs, including a U-shaped frame member having a web portion disposed opposite to but spaced from the edges of the laminations, a lubricant container between said edges and said web, and a spring for holding 70 said container against the edges of the laminations, said last mentioned spring encircling said container and disposed between said web portion and said container.

9. A lubricating device for laminated springs including a lubricant container having an open end and a peripheral flange, an annular gasket engaging with the face of said flange, and means engaging with said container for forcing said gasket against the edge of the spring to permit direct contact 85 of the lubricant through the center opening of the gasket.

10. A lubricating device for laminated springs including a lubricant container having an open end and a peripheral flange, an annular gasket engaging with the face of said flange, and means engaging with said container for forcing said gasket against the edge of the spring to permit direct contact 90 of the lubricant through the center opening of the gasket, said means including a frame member having an aperture receiving said container but smaller than said flange.

11. A lubricating device for laminated springs, including a lubricant container having an open end and a peripheral flange, an annular gasket engaging with the face of said flange, a frame having an opening receiving said container but smaller than said flange, and a spring encircling 100 said container between said frame and said flange.

Signed at New York, in the county of New York and State of New York, this 11th day of April A. D. 1923.

SAMUEL BARUCH.
